CLAIM

The ornamental design for a retractable lanyard, as shown and described.

DESCRIPTION

FIG. 1 is a perspective view of a retractable lanyard showing my design;

FIG. 2 is a top plan view thereof;

FIG. 3 is bottom plan view thereof;

FIG. 4 is right side elevation view thereof;

FIG. 5 is a left side elevation view thereof;

FIG. 6 is a front elevation view thereof;

FIG. 7 is a rear elevation view thereof;

FIG. 8 is a perspective view of a retractable lanyard showing a second embodiment of my new design;

FIG. 9 is a top plan view of FIG. 8;

FIG. 10 is bottom plan view of FIG. 8;

FIG. 11 is right side elevation view of FIG. 8;

FIG. 12 is a left side elevation view of FIG. 8;

FIG. 13 is a front elevation view of FIG. 8;

FIG. 14 is a rear elevation view of FIG. 8;

FIG. 15 is a perspective view of a retractable lanyard showing a third embodiment of my new design;

FIG. 16 is a top plan view of FIG. 15;

FIG. 17 is bottom plan view of FIG. 15;

FIG. 18 is right side elevation view of FIG. 15;

FIG. 19 is a left side elevation view of FIG. 15;

FIG. 20 is a front elevation view of FIG. 15; and,

FIG. 21 is a rear elevation view of FIG. 15.
